UNITED STATES PATENT OFFICE.

KELLEY M. TURNER, OF NEW YORK, N. Y., ASSIGNOR TO GENERAL ACOUSTIC CO.,
A CORPORATION OF NEW YORK.

VISUAL SIGNAL AND KEY.

No. 861,001.

Specification of Letters Patent.

Patented July 23, 1907.

Application filed March 6, 1907. Serial No. 360,921.

To all whom it may concern:

Be it known that I, KELLEY M. TURNER, a citizen of the United States, residing at New York city, in the county of New York and State of New York, have invented certain new and useful Improvements in Visual Signals and Keys, of which the following is a full, clear, and exact description.

My invention relates to signal apparatus for telephone systems, particularly the type known as visual signals, and which are employed with a key by which the circuits corresponding to the signals are controlled.

In telephone apparatus, and particularly in the use of switchboards, and also in connection with the dictating apparatus described in Patent No. 843,186, mechanical signals are used to display or drop a shutter whenever a battery current is applied to the corresponding line for signaling purposes. These signals are of two types, one in which a shutter is released to drop by gravity, and to remain in such dropped relation until specially restored, and another form in which a shutter is raised against the force of gravity by an electromagnet and only held displayed as long as the magnet is energized. Signals of the first type have been made "self-restoring" by auxiliary magnets and cams, but so far as I am aware, the functions of this class of signals have never been attained by signals of the second class or "visual signals". In other words, visual signals have been displayed only as long as their magnets were energized. They have not been adapted to retain their signal displayed beyond the time of such energization, and so far as I am aware, they have not been self-restoring in the sense of ceasing their signal when a predetermined act or operation is performed, as, for example, the movement of the operator's key for their particular circuits.

In carrying out my invention I aim to provide a visual signal having these characteristics, and further to construct it in a very simple, compact and efficient way, and so as not to interfere with its sensitiveness of operation.

With this object in view, the invention consists in the features of construction and combination hereinafter set forth and claimed.

In the drawings: Figure 1 is a side view of a combined visual signal and key embodying the principles of my invention; Fig. 2 is a sectional view of the same on the line II-II of Fig. 1; Fig. 3 is a view similar to Fig. 1, but showing the shutter in a position to display a signal.

Referring to the drawings in which like parts are designated by the same reference sign, 1 indicates the usual iron-clad magnet, having an armature 2, pivoted thereon at the point 3. This magnet is mounted on the

usual metallic frame 4, having an opening 5, for the display of the visual signal, and having a circuit controlling key 6. The circuit controlling key is of the ordinary construction having insulating cans or roller 7, which press against the spring contact blades in uses. The target or shutter of the visual signal is indicated at 8, and is fixed to an arm or extension 9, from the armature 2. The relation is such that when the armature 2 is attracted by its magnet, the target 8 moves upward to a position opposite the opening 5. These features thus far described constitute the ordinary and well known construction of telephone signal and key, and in themselves form no part of my invention. At the point 10 upon the frame 4, I pivot a lever 11, of very light and delicate construction. At one extremity of this lever there is an enlargement, pawl or detent 12, which is capable of moving behind the armature 2 when the latter is attracted so as to restrain the same in its attracted relation. The other end of the lever 11 is formed with a downward extension 13, and the balance is such that the detent 12 is pressed upward very lightly against the edge of the armature 2. For this purpose it is merely necessary to have the weight of the end 13 of the lever great enough so that its moment about the pivot 10 is greater than the moment of the other end or arm of the lever. It is evident that the lever can be properly weighted to secure this result regardless of the particular position of the pivot 10 thereon. The extension 13 of this lever is in the path of a stud 14, which projects from a movable part of the key 6, and preferably from the spindle of the rollers 7. In this way the extension 13 is engaged by such stud 14 whenever the key is operated, and the extension is thereby caused to move the lever in a direction to depress the detent 12 and release the armature 2 from its attracted relation on the electromagnet. It is obvious that any desired movement of the key may accomplish this result, but I have in practice utilized the movement of the key which establishes the talking circuits with the party signaling.

The operation is as follows: Supposing a call to be received at the signal while the party thereat is away, or his attention otherwise engaged. The target or shutter 8 is raised opposite the opening 5 by the electromagnet 1, and is constrained to continue in this relation by the detent 12 which falls behind the armature in its attracted relation. The signal therefore continues to display although the party making the call has discontinued the signaling current. When finally the called party returns, he is notified of the call received and moves his key to ring or telephonically connect with the party who initially desired communication. In the form of the invention shown the visual

signal ceases to be displayed as soon as the talking circuits have been completed, so that the operator does not have to give any attention to the signal. This visual signal therefore accomplishes all of the functions 5 in connection with the key, of the self-restoring drop signal which has been used with the plug and jack.

What I claim, is:—

1. In a signaling device, a magnet, an armature pivoted thereto, said armature having an arm or extension terminating in a target, a key pivoted to swing in a plane adjacent to the magnet, spring blades deflected by swinging movements of said key in either direction from its normal or central position, a pivoted detent lever movable into a position to engage said armature, and means fixed to said
- 10

key and engaging said detent lever for displacing it from 15 such relation.

2. In combination with a visual signal having a magnet and an armature with a target or shutter, a key having spring contact blades and cam rollers, a stud mounted on said key, a lever having a detent for restraining said armature in position to exhibit a signal, and an extension on said lever in the path of said stud by which the armature is released.

In witness whereof, I subscribe my signature, in the presence of two witnesses.

KELLEY M. TURNER.
